[57] **ABSTRACT**

This is a two-piece refractory anchor which utilizes a jamb fit between a stud and the arms of the anchor to allow adjustment and movement of the arms of the anchor when the refractory moves in relation to its support.

TWO-PIECE REFRACTORY ANCHOR FOR HEAVY DUTY CONSTRUCTION

BACKGROUND OF THE INVENTION

A kiln generally consists of an outer metal sheet and an inner lining. Some kilns are of the rotary type. The inner lining of the kiln may be formed of brick or may be of monolithic one-piece type. The monolithic type can be cast directly against the inner side of the outer shell of the kiln. With the use of "RotoCast" or similar methods the lining is installed in one continuous pour per section forming a single "L" length. In some cases through the use of full circular cast lining method a homogenous monolithic installation is achieved with but a single longitudinal cold joint.

A difficulty with linings in rotary kilns is that there is a moving or rifling of the lining in relation to the shell. The rifling is dependent upon several interacting forces such as the diameter of the shell and the speed of rotation of the kiln. Because a monolithic castable lining is truly one-piece, the forces act on the entire unit and are multiplied to a great extent causing severe stress on the anchors.

DESCRIPTION OF PRIOR ART

One method of holding the shell and the lining together is to provide a series of V-shaped end weldable studs as disclosed in the patent to Barkley, U. S. Pat. No. 3,336,712. The studs are hand tack welded to the shell. When the lining moves in relation to the shell, the lining tends to crack into discrete units of varying size while simultaneously subjecting the stud or anchors to shear stress which may break the anchors thus allowing the broken pieces of the lining to fall away from the shell.

Another method of holding the lining to the shell is to use two-piece anchors, one element of which is a rectangular nut having an aperture formed therethrough welded to the shell, the arm portion of the fastener is passed through the hole and tack welded to the nut. This type of arrangement still requires a weld operation. Movement of the lining may or may not break the anchor-nut weld, so that this anchor suffers from the same liabilities as the first type.

SUMMARY OF THE INVENTION

This invention is directed at a two-piece refractory anchor for kiln construction.

An object of the present invention is to provide a refractory anchor in which the arms are not welded to the support.

A further object of the present invention is to provide a two-piece refractory anchor in which the arms are adapted to collapse in relation to the stud.

A still further object of the invention, is to provide a two-piece refractory anchor in which one of the elements is a pair of arms connected by a bight portion and the other element is a cylindrical stud having an aperture formed therethrough whereby placing the arms in a certain relation to the stud the two elements are locked together.

BRIEF DESCRIPTION OF THE DRAWINGS

FIG. 1 is a section partly in elevation of the prior art con-

struction.

FIG. 2 is a side elevation broken off showing a portion of the shell and several studs attached thereto.

FIG. 3 is a side elevation showing the arms loosely engaged to a stud.

FIG. 4 is a side elevation showing the arms engaged under tension to the stud.

FIG. 5 is a section taken on line 5-5 of FIG. 4 showing the anchor element in side elevation.

FIG. 6 is a section taken on line 6-6 of FIG. 3 showing the anchor element in side elevation.

FIG. 7 is a perspective of the assembly of FIG. 4.

DESCRIPTION OF THE PREFERRED EMBODIMENT

In the drawings there is shown in FIG. 1 a prior art refractory anchor comprising the shell 10 of kiln, such as a rotary kiln, a lining 12 formed of a refractory material and applied to the shell either by blowing or spraying to provide a monolithic construction and the anchor 14. The anchor 14 is generally V-shaped in configuration and is welded directly to the shell 10 at its bight portion. The inventors' anchor and assembly is shown in FIGS. 2 through 7 and includes a stud element 16 and an anchor element which has a bight portion 18 and a pair of arms 20. The stud element 16 comprises a metal cylinder having a circular hole 22 formed transversely therethrough. The diameter of the circular hole 22 is greater than the diameter of the arm 20. And the diameter of the stud element 16 is such that the anchor element can be passed, on a plane at right angle to the axis of the stud element 16, through the hole 22 without binding and can be left, with an arm 20 on each side of the stud element 16 hanging loosely. If each of the stud elements 16 were welded to a shelf 24 of a kiln as shown in FIG. 2, the arms 20 would hang loosely with the bight portion 18 within the hole 22. Rotating the arms 20 upwardly away from the shell 24 will cause the outer surface of the bight portion 18 and the inner surface of each of the arms 20 to butt against the inner surfaces of the wall defining the hole 22 thereby forcing the arms against the edge of the surface of the wall defining the upper portion of the hole 22 and the bight portion against the surface of the wall defining the lower portion of that hole. The dimension of the hole 22 and its relation to the angle of the bight portion 18 causes a jamming action at three (3) places holding the anchor element engaged to the stud element 16.

With references to the foregoing description it is to be understood that what has been disclosed herein represents an embodiment of the invention and is to be construed as illustrative rather than restrictive in nature and that the invention is best described by the following claims:

1. An anchor for a kiln or the like comprising a stud having a wall defining a transverse aperture formed therethrough and a U-shaped anchor element having a pair of arms connected by a bight portion, each of the arms having an uninterrupted inner surface and a bight portion having an outer surface, the diameter of the arms, the angle of the bight, the diameter of the stud and the length of the transverse cord taken at the center of the aperture is such that the anchor element will bind when moved from a first position to an upright position with the bight in the aperture.
